UNITED STATES PATENT OFFICE.

FRANKLIN M. LAWRENCE, OF PORTLAND, MAINE.

DESIGN FOR A COOKING-RANGE.

No. 88,225.

Specification for Design.

Patented Sept. 4, 1906.

Application filed June 23, 1906. Serial No. 323,124. Term of patent 3½ years.

To all whom it may concern:

Be it known that I, FRANKLIN M. LAWRENCE, a citizen of the United States, residing at Portland, in the county of Cumberland and State of Maine, have invented a new, original, and ornamental Design for Cooking-Ranges, of which the following is a specification, reference being had to the accompanying drawing, forming part thereof.

The figure is a perspective view of a range, showing my new design.

I claim—

The ornamental design for a cooking-range as shown.

FRANKLIN M. LAWRENCE.
